(57) CLAIM

The ornamental design for a storage rack, as shown and described.

DESCRIPTION

FIG. 1 is a perspective view of a storage rack of the invention;

FIG. 2 is a top view;

FIG. 3 is a front view of FIG. 1;

FIG. 4 is a bottom view of FIG. 1;

FIG. 5 is a back view of FIG. 1; and,

FIG. 6 is a left side view of FIG. 1, the right side being identical thereto.

The broken lines shown are for illustrative purposes only and form no part of the claimed design.
